APPARATUS FOR MINING COAL

Charles B. Officer, Chicago, Ill., assignor to Sullivan Machinery Company, a corporation of Massachusetts

Application August 28, 1934, Serial No. 741,810

23 Claims. (Cl. 262—30)

This invention relates to an apparatus for mining coal or similar materials, and more particularly to improvements in a kerf cutting, breaking down and conveying means whereby the mine wall may be cut and the coal broken down and conveyed from the face by a self-contained unitary apparatus movable along the face of the coal.

An object of this invention is to provide an improved apparatus for mining coal whereby the coal is cut, broken down and conveyed from the face in an improved manner by a unitary mechanism embodying kerfing, breaking down and conveying means. Another object is to provide an improved kerf cutting means for cutting parallel horizontal top and bottom kerfs in a mine wall and a rear wall vertical kerf intersecting said horizontal kerfs for cutting out from the mine wall a core of coal. A further object is to provide an improved kerfing means for cutting out a core of coal from the coal face in a direction parallel with the coal face and having associated therewith means for breaking down the core as cutting progresses. Yet another object is to provide in an apparatus of the above character a conveying means for receiving the coal broken down by the breaking down means and for conveying the broken coal away from the coal face. Still another object is to provide a coal mining apparatus of the longwall type adapted to move during its operation in a direction parallel with the coal face and having embodied therein improved kerfing, breaking down and conveying means whereby the coal is cut to form a core and the core thereafter broken down and conveyed away from the coal face. Yet another object is to provide an improved mining apparatus comprising means for cutting parallel horizontal kerfs respectively at the roof and floor, thereafter cutting a vertical rear wall kerf intersecting said parallel horizontal kerfs, breaking down the core of coal formed by said horizontal and vertical kerfs as cutting progresses, and finally conveying away the broken down coal. These and other objects will, however, hereinafter more fully appear in the course of the following description and as more particularly pointed out in the appended claims.

In the accompanying drawings there is shown for purposes of illustration one form which the invention may assume in practice.

In these drawings,—

Fig. 1 is a plan view of the illustrative embodiment of the improved mining and loading apparatus showing its association with a mine wall,

Fig. 2 is a side elevational view of the mining and loading apparatus shown in Fig. 1.

Fig. 3 is an enlarged vertical sectional view taken substantially on line 3—3 of Fig. 1.

Fig. 4 is a horizontal sectional view taken substantially on line 4—4 of Fig. 3, with parts omitted to facilitate illustration.

Fig. 5 is an enlarged, longitudinally extending, vertical sectional view taken substantially on line 5—5 of Fig. 1.

Fig. 6 is a detail view showing the swinging mechanism for the vertical kerf cutter.

Fig. 7 is a detail sectional view taken on line 7—7 of Fig. 6.

Fig. 8 is a detail sectional view showing a portion of the breaking down means.

Fig. 9 is a cross sectional view taken on line 9—9 of Fig. 8.

Fig. 10 is a longitudinally extending vertical sectional view taken on line 10—10 of Fig. 8.

In this illustrative embodiment of the invention there is shown a mining and loading apparatus for cutting out a core of coal from the mine wall, breaking down the core as cutting progresses and for conveying the broken down coal away from the coal face; this improved apparatus, in this instance, being of the longwall type and adapted to move along the mine wall in a direction parallel with the coal face during the mining and loading operation. This improved mining and loading apparatus is herein, for illustrative purposes, shown as the flexibly fed longwall type adapted to rest upon and slide over the mine floor during the cutting operation, but it will be evident that if desired the improved mining and loading apparatus may be of the wheel mounted, track supported and guided type adapted to run along a mine trackway laid on the mine floor in a direction parallel with the coal face or of the crawler tread mounted type, and that features of the invention may be associated with mining and loading apparatus of various types other than that disclosed.

In this illustrative construction there is shown a horizontal kerf cutting unit generally designated 1 and a vertical kerf cutting, breaking down, and conveying unit generally designated 2, these units being connected together for movement in unison bodily along the mine wall and having common propelling means whereby the entire apparatus is slid bodily over the mine floor as cutting, breaking down, and loading progresses.

The horizontal cutting unit 1 comprises a frame 3 having a smooth bottom surface 4 adapted to rest upon and slide over the mine floor. Piv-

55

totally mounted on the rearward portion of the frame 3 is a pair of superimposed horizontal kerf cutters 5 and 6, the former comprising a top horizontal kerf forming means for forming a kerf in 5 horizontal planes adjacent the mine roof while the latter comprises a bottom horizontal kerf forming means for cutting a horizontal kerf in planes adjacent the mine floor. The top kerf cutter 5 is vertically adjustable into different 10 parallel horizontal cutting positions with respect to the bottom kerf cutter to provide sufficient flexibility so as to enable the apparatus to cut parallel horizontal kerfs in coal seams of varying height. The kerf cutters 5 and 6 are pivotally mounted 15 on the machine frame for horizontal swinging movement relative thereto about a common vertical axis and are mounted on the machine frame for independent swinging movement. The frame 3 carries a motor 7 having fixed to its power shaft 20 8 a bevel pinion 9 meshing with a bevel gear 10 journaled on a vertical shaft 11 suitably mounted within the cutter frame section 12 of the machine frame. Driven by this bevel gear is a spur gear 13 meshing with a spur gear 14 journaled on 25 a vertical shaft 15 likewise suitably mounted in the cutter head frame 12. Mounted coaxially with the shaft 15 and connectible to the gear 14 as by a usual sliding pin clutch 16 is a chain sprocket 17 for engaging and driving an endless 30 cutter chain 18 mounted on the margin of an elongated plane cutter bar 19 of the lower kerf cutter 6. The spur gear 14 drives the vertical shaft 15 and this shaft constitutes an element of a telescopic torque shaft, and is splined at 35 20 to a tubular shaft 21 suitably journaled in a vertically adjustable supporting frame 22 for the top kerf cutter 5. Keyed to the tubular shaft 21 and driven thereby is a chain sprocket 23 which engages and drives an endless cutter chain 24 40 mounted for circulation about the margin of an elongated plane cutter bar 25 of the top kerf cutter 5. The bottom cutter bar 19 of the kerf cutter 6 is journaled for horizontal swinging movement with respect to the frame at 26 on a 45 step plate 27 secured to the frame bottom and is guided for horizontal swinging movement on an arcuate flange 28 integral with the cutter frame section 12. The flange 28 is provided with a series of openings 29 for receiving a locking pin 30 50 and this locking pin engages openings 31 in the bar for locking the latter in its different angular positions about its pivot. The top cutter bar 25 is journaled at 32 on a head 33 bolted to the vertically adjustable frame 22 and the bar has an 55 annular frame portion 34 rotatable relative to the frame 22 and adapted to be locked with the latter in its different adjusted positions by a locking pin 35 thereby to lock the top cutter bar in its different angular positions. For adjusting the 60 top cutter bar vertically with respect to the machine frame there is provided a screw 36, herein of tubular form, surrounding the tubular shaft 21 and formed integral with the head 33. Threadedly engaging the screw 36 is a rotatable nut 37 65 journaled on the cutter head frame 12 and slidably engaging a tubular guide portion 38 of the frame for guiding the vertically adjustable frame 22 during the vertical adjustment of the top cutter bar. Formed integral with the nut 37 is a worm wheel 39 with which meshes a worm 40 secured to a longitudinally extending worm rotating shaft 41. This shaft overlies the top of the machine frame as shown in Fig. 1 and has secured 70 75 to its forward end at the forward end of the ma-

chine frame a shaft rotating handle 42. It will thus be seen that the parallel kerf cutters may be independently swung with respect to the machine frame and that the top kerf cutter may be adjusted vertically into different parallel cutting planes with respect to the bottom cutter. The horizontal cutting unit 1 may be propelled in various manners, but is, in this instance, provided with a usual flexible feeding means comprising a flexible feed chain 43 engaging a rotatable feed 5 sprocket 44 mounted on the machine frame and driven by the motor 7 in the manner disclosed in the patent to Holmes, No. 1,544,398 granted June 30, 1925. The free end of this feed chain 43 is connectible to a suitable anchor located in advance of the mining and loading apparatus in adjacency to the mine wall, and as the chain sprocket 44 is rotated to draw in the feed chain the entire mining and loading apparatus is moved bodily over the mine floor in a direction parallel 10 with the coal face. The free end of the feed chain 43 is also connectible to a projection 45 formed on the lower kerf cutter for swinging the latter with respect to the machine frame and to a hook-like projection 46 formed on the top kerf cutter for swinging the latter with respect to the machine frame. The manner of swinging the kerf cutters about their respective pivots is clearly described in the above mentioned patent to Holmes. It will thus be seen that the parallel horizontal kerf cutters may be swung about their pivots to effect sumping thereof within the coal 15 face and may be locked in their right angled position, as shown in Fig. 1, against swinging movement with respect to the machine frame. The cutter chains of the kerf cutters may then be rapidly circulated about the margins of their cutter bars, and as the machine frame is fed over the mine floor by the flexible feeding means, parallel horizontal kerfs are cut in the mine wall in 20 planes adjacent the mine floor and mine roof respectively. 25

Now referring to the vertical kerf cutting, breaking down and conveying unit 2, it will be noted that the same comprises a bed frame 47 having a plane bottom surface 48 adapted to rest upon and slide over the mine floor. Mounted on this bed frame 47 is a loading and conveying means comprising a coal receiving shovel or scoop 49, a front elevating conveyor 50 and a rear discharge conveyor 51. Pivotally mounted on the bed frame at the inner side of the elevating conveyor 50 for cutting a rear wall vertical kerf at the rear side of the mine wall in planes parallel with the coal face is a vertical kerf cutter 52. 30 This kerf cutter comprises a plane cutter bar 53 having mounted for circulation about its margin an endless cutter chain 54 and is pivotally mounted on the bed frame for swinging movement in a vertical direction. The means for driving the cutter chain comprises a motor 55 mounted on the bed frame 47 at the outer side of the elevating conveyor 50, and this motor drives through bevel gearing 56 a horizontal shaft 57 herein extending transversely of the bed frame. Keyed to this shaft is a gear 58 meshing with a gear 59 fixed to a parallel shaft 60 extending beneath the elevating conveyor 50, and keyed to the inner end of the shaft 60 is a spur gear 61 meshing with a spur gear 62 suitably fixed to a shaft 63 aligned with the bar pivot axis. Keyed to the shaft 63 and driven thereby is a chain sprocket 64 which engages and drives the cutter chain 54. Any suitable form of cutter chain clutch 35 may be provided for disconnecting the cutter 40 45 50 55 60 65 70 75 80 85 90 95 100

chain from its drive. The means for swinging the vertical kerf cutter about its pivot may assume various forms, but herein comprises a hydraulic cylinder 65 mounted on the bed frame at 5 the inner side of the elevating conveyor 50 and having reciprocable therein a piston 66. Secured to this piston is a piston rod 67 connected to a crosshead 68 mounted in a guideway 69 secured to the side of the bed frame. Pivotedly connected 10 to this crosshead at 70 is a link 71 in turn pivotally connected at 72 to an arm 73 suitably fixed to the cutter bar 53. Liquid under pressure may be supplied to the opposite ends of the cylinder 65 through suitable pipe connections 74 and 75 15 from any suitable source of supply, as by a pump driven by the motor 55 and under the control of any suitable valvular control means. It will thus be seen that the vertical kerf cutter may be swung vertically about its pivot and may be held in any of its adjusted positions by the cylinder 65. As the mining and loading apparatus moves along the mine wall the vertical kerf cutter cuts a rear wall kerf intersecting the parallel horizontal kerfs, thereby to form a core of coal 20 25 30 35 40 45 50 55 60 65 70 75 76 as cutting progresses. The elevating conveyor 50 comprises endless conveyor chains 77 mounted in suitable guideways 78 formed on a frame 79 mounted on the bed frame 47, and this endless conveyor is driven from the motor 55 by a gear 80 meshing with the gear 58 fixed to the shaft 57. This gear 80 is fixed to a horizontal shaft 81 extending transversely of the bed frame beneath the elevating conveyor 50 and has fixed thereto chain sprockets 82, 82 which engage and drive the endless chains 77 of the conveyor. The front conveyor 50 discharges onto the discharge conveyor 51, and this latter conveyor has a swivel frame 83 rotatably mounted in an annular guideway 84 secured to the bed frame 47. This conveyor comprises endless conveyor chains 85 mounted in suitable guideways 86 formed on the discharge conveyor frame 87 mounted on the frame 83. This conveyor is swingable horizontally with respect to the bed frame and is, in this instance, driven by a motor 88 mounted on the side of the frame 87 and driving through worm gearing 89 a transverse shaft 91 suitably journaled on the frame 87. Fixed to this shaft are chain sprockets 92, 92 which engage and drive the conveyor chains 85. This rear discharge conveyor 51 is disposable and may be suitably locked in a position at right angles with respect to the mining and loading apparatus as shown in Fig. 1 and discharges on a suitable face conveyor 93 located outside the coal face in a direction parallel with the latter and inside the roof props 94 in the manner shown. The bed frame 47 is provided with upstanding frame portions 95, 95 connected by suitable connecting means such as tie rods 96, 96 to the machine frame 3 of the horizontal cutting unit 1 so that when the horizontal cutting unit is moved along the coal face by the flexible feeding means 43 the vertical kerf cutting and conveying unit 2 is moved bodily therewith, the flexible feeding means 43 constituting a common feeding means for both units so that the entire cutting, breaking down and loading apparatus is moved bodily along the coal face over the mine floor.

The means for breaking down the core 76 as cutting progresses may assume various forms, but is herein in the form of a pick generally designated 97 and comprises a frame 98 mounted to swing vertically about a horizontal axis 99. The frame 98 has parallel guides 100, 100 in

which are reciprocably mounted guide portions 101, 101 of a reciprocating pick frame 102. The frame 102 is armed at its forward edge with a series of picking tools 103. The movement of the reciprocating frame with respect to the frame 98 is limited by screws 104 projecting within longitudinal slots 105 formed in the frame 102, while interposed between the guide portions 101 and the frame 98 are coiled springs 106, 106, these springs normally urging the reciprocating frame towards its outermost position with respect to the frame 98. The swinging frame 98 is journaled at 107 on upstanding brackets 108 mounted on the bed frame 47 and the means for swinging the pick frame about its pivot 99 with respect to the bed frame in this instance comprises a hydraulic cylinder 109 mounted on the outer side of the frame 79 of the elevating conveyor 50 and having reciprocable therein a piston 110. Secured to this piston is a piston rod 111 connected to an arm 112 secured to the swinging frame 98. Fluid under pressure may be supplied to this cylinder 109 through the same source of supply and under similar control as that for the swinging cylinder 65 of the vertical kerf cutter. The means for reciprocating the frame 102 with respect to the swinging frame 98 comprises a motor 113 mounted on the bed frame 47 and driving a gear 114 meshing with a gear 115. The gear 115 is keyed to a horizontal transversely extending shaft 116 suitably journaled in the brackets 108. Keyed at 117, 117, to the shaft 116 are cam-like arms 118 having cam portions adapted to engage projecting lugs 119 formed on the reciprocating pick frame 102. As the shaft 116 is rotated the levers 118 engage the lugs 119 to move the reciprocating frame 102 rearwardly against the tension of the springs 106 and thereafter release from the lugs 119. Upon release of the cam projections from the lugs on the reciprocating frame the springs 106 drive the picks 103 forwardly to engage percussively the core of coal formed by the kerf cutters to break down the core. As the pick 103 is reciprocated, it may be swung upwardly and downwardly by the hydraulic cylinder and piston 109, 110, thereby to break down the entire rear wall of the core. The swinging frame 98 of the pick device is mounted to straddle the elevating conveyor and is so formed as to enable the coal received by the elevating conveyor to pass beneath the same. As the coal is broken down by the picking device it is received by the scoop or shovel 49 and moved rearwardly by the front conveyor 50 onto the discharge conveyor 51 which in turn discharges laterally onto the face conveyor 93.

From the foregoing it will be seen that as the mining and loading apparatus is propelled along the mine wall superimposed parallel horizontal kerfs are cut in the mine wall in planes adjacent the floor and roof, respectively, and thereafter a vertical rear kerf is cut in the mine wall in planes intersecting the parallel horizontal kerfs thereby to form a core. The core is then broken down from the mine wall by the picking device and thereafter the broken down coal is conveyed from the face by the elevating and discharge conveyors. It will be noted that the apparatus is entirely self-contained and operates to cut, break down and load the coal directly from the mine wall by a series of coordinated operations so that as the apparatus is propelled along the mine wall the coal is entirely removed from the coal seam. By adjustment of the top kerf cutter into differ-

ent parallel horizontal planes and by swinging the vertical kerf cutter 52 the apparatus may operate on coal seams of varying height. These and other uses and advantages of the improved mining and loading apparatus will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

15 What I claim as new and desire to secure by Letters Patent is:

1. In a mining and loading apparatus, a portable base movable along a coal face outside thereof in a direction parallel with the coal face, 20 means mounted on said base for simultaneously cutting parallel horizontal kerfs in the mine wall, respectively at the floor and roof levels, a portable base movable along the coal face inside the latter in a direction parallel with the coal face, 25 means mounted on said second base for cutting a rear wall vertical kerf, said kerfs extending in a direction parallel with the coal face and cooperating to form a core of coal, means on said second base inside the coal face for dislodging 30 sections of the core as cutting progresses thereby to form an opening in the mine wall of such size as to provide clearance for said second base as the apparatus is advanced along the coal face, receiving means carried by said second base for 35 receiving the dislodged coal and for conveying the dislodged coal laterally from the coal face, and propelling means for the apparatus for moving said bases in unison bodily along the coal face.

40 2. In a mining and loading apparatus, a portable base movable along a coal face outside thereof in a direction parallel with the coal face, means mounted on said base for simultaneously cutting parallel horizontal kerfs in the mine wall, 45 respectively at the floor and roof levels, a portable base movable along the coal face inside the latter in a direction parallel with the coal face, means mounted on said second base and arranged rearwardly of said horizontal kerf cutting means 50 for cutting a rear wall vertical kerf, said kerfs extending in a direction parallel with the coal face and cooperating to form a core of coal, means on said second base inside the coal face for dislodging sections of the core as cutting progresses 55 thereby to form an opening in the mine wall of such size as to provide clearance for said second base as the apparatus is advanced along the coal face, means carried by said second base for receiving the dislodged coal and for conveying the 60 dislodged coal away from the coal face, and propelling means for the apparatus for moving said bases in unison bodily along the coal face.

65 3. In a mining and loading apparatus, a portable base movable along a coal face outside thereof in a direction parallel with the coal face, means mounted on said base for simultaneously cutting parallel horizontal kerfs in the mine wall, 70 respectively at the floor and roof levels, a portable base movable along the coal face inside the latter in a direction parallel with the coal face, means mounted on said second base and arranged rearwardly of said horizontal kerf cutting means for cutting a rear wall vertical kerf, 75 said kerfs extending in a direction parallel with the coal face and cooperating to form a core

of coal, means on said second base inside the coal face for dislodging sections of the core as cutting progresses thereby to form an opening in the mine wall of such size as to provide clearance for said second base as the apparatus is advanced along the coal face, means mounted on said second base inside the coal face for conveying the dislodged coal in a rearward direction parallel with the coal face, means on said second base for thereafter conveying the dislodged coal in a direction laterally of the coal face away from the coal face, and propelling means for the apparatus for moving said bases in unison bodily along the coal face.

4. In a mining and loading apparatus, a portable base movable along a coal face outside thereof in a direction parallel with the coal face, means mounted on said base for simultaneously cutting parallel horizontal kerfs in the mine wall, respectively at the floor and roof levels, a portable base movable along the coal face inside the latter in a direction parallel with the coal face, means mounted on said second base and arranged rearwardly of said horizontal kerf cutting means for cutting a rear wall vertical kerf, 25 said kerfs extending in a direction parallel with the coal face and cooperating to form a core of coal, means on said second base inside the coal face for dislodging sections of the core as cutting progresses thereby to form an opening in the mine wall of such size as to provide clearance for said second base as the apparatus is advanced along the coal face, means mounted on said second base inside the coal face for conveying the dislodged coal in a rearward direction 30 parallel with the coal face, means on said second base for thereafter conveying the dislodged coal in a direction laterally of the coal face away from the coal face, propelling means for the apparatus for moving said bases in unison bodily along the coal face.

35 5. In a mining and loading apparatus, a portable base movable along a coal face outside thereof in a direction parallel with the coal face, means mounted on said base for simultaneously cutting parallel horizontal kerfs in the mine wall, 40 one kerf at the floor level and the other at a substantial distance above the floor level, and comprising parallel kerf cutters, means on said base for adjusting the top kerf cutter in a vertical direction with respect to said bottom kerf cutter, a portable base movable along the coal face inside the latter in a direction parallel with the face, means mounted on said second base and arranged rearwardly of said horizontal kerf cutting means for cutting a rear wall vertical kerf 45 and comprising a vertical kerf cutter, said vertical kerf cutter swingable in a vertical direction relative to said second base, and all of said kerf cutters cooperating to form a core of coal in a direction parallel with the coal face, means on said second base inside the coal face for breaking down the rear wall of the core as cutting progresses thereby to form an opening in the mine wall of such size as to provide clearance for said second base as the apparatus is advanced along the coal face, conveying means carried by said second base for receiving the broken down coal and conveying the coal away from the coal face, and propelling means for the apparatus for 50

moving said bases in unison bodily along the coal face.

6. In a mining and loading apparatus, a portable base movable along a coal face outside there-
5 of in a direction parallel with the coal face, kerf forming means mounted on said base for cutting simultaneously parallel horizontal kerfs in the mine wall in a direction parallel with the coal face, a portable base movable along the coal face
10 inside the latter in a direction parallel with the coal face, kerf forming means mounted on said second base for cutting a rear wall vertical kerf intersecting said horizontal kerfs, said kerf forming means cooperating to cut out a core of coal
15 in the mine wall in a direction parallel with the coal face, means on said second base for breaking down fragments of the core as cutting progresses to form an opening in the mine wall of such size as to provide clearance for said second base as
20 the apparatus is advanced along the coal face, receiving means on said second base for receiving the dislodged coal and for conveying the dislodged coal laterally from the coal face, means on said first base for varying the distance apart of said horizontal kerfs by adjusting the top kerf cutter in a vertical direction with respect to the bottom kerf cutter, means on said second base for swinging said vertical kerf cutter in a vertical direction, and propelling means for the apparatus for mov-
30 ing said bases in unison bodily along the coal face.

7. A mining and loading apparatus comprising a kerf cutting unit for forming simultaneously parallel horizontal kerfs in the coal face in a direction parallel with the coal face, a vertical kerf forming, breaking down, and conveying unit supported independently of said horizontal kerf cutting unit for cutting a vertical rear wall kerf intersecting said horizontal kerfs, for breaking down the coal as cutting progresses and for conveying the coal broken down away from the coal face, said second mentioned unit spaced longitudinally of the coal face rearwardly of said first mentioned unit, and means extending between said units for connecting said units together for
45 movement in unison along the coal face.

8. In a mining and loading apparatus, a horizontal cutting unit including parallel superimposed kerf cutters for cutting parallel horizontal kerfs in a mine wall, a cutting, dislodging and
50 loading unit including a vertical kerf cutter for cutting a vertical kerf intersecting said parallel horizontal kerfs, devices acting on the rear wall of a block of coal formed by said horizontal and vertical kerfs for dislodging the coal and conveying means for the broken down coal, said second mentioned unit spaced longitudinally of the coal face rearwardly of said first mentioned unit, means for connecting said second mentioned unit to said first mentioned unit for movement there-
55 with, and feeding means embodied in said first mentioned unit for feeding said units in unison along the mine wall.

9. In a mining and loading apparatus, a cutting unit including parallel superimposed horizontal
65 kerf cutters for cutting parallel horizontal kerfs in a mine wall including a frame arranged outside and parallel with the coal face and on which said kerf cutters are mounted, means for feeding said frame along the coal face, a cutting, dislodging and loading unit including a vertical kerf cutter for cutting a vertical kerf intersecting said horizontal kerfs, a frame movable in a direction parallel with the coal face inside the latter and on
70 which said vertical cutter is mounted, dislodging means mounted on said last mentioned frame for
75

breaking down the coal cut by said horizontal and vertical kerf cutters and means on said frame for conveying the broken down coal, said second mentioned unit spaced longitudinally of the coal face rearwardly of said first mentioned unit, and means for connecting said second mentioned unit to said first mentioned unit for movement therewith.

10. In a mining and loading apparatus, a horizontal cutting unit for cutting parallel horizontal kerfs in a mine wall, a vertical cutting unit for cutting a vertical kerf intersecting said parallel horizontal kerfs, said second mentioned unit spaced longitudinally of the coal face rearwardly of said first mentioned unit, tie rods for connecting said vertical cutting unit to said horizontal cutting unit for movement therewith, and means for feeding said horizontal cutting unit.

11. In a mining and loading apparatus, a portable base movable along a coal face outside there-
20 of in a direction parallel with the coal face, horizontal kerf cutting means mounted on said base for cutting simultaneously parallel horizontal kerfs in the mine wall, a portable base movable along the coal face inside the latter in a direction parallel with the coal face, vertical kerf cutting means mounted on said second base for cutting a vertical kerf intersecting said horizontal kerfs, said kerf cutting means cooperating to cut out a block of coal from the mine wall, breaking down
25 means mounted on said second base and arranged inside the coal face rearwardly of the forward extremity of said vertical kerf forming means for breaking down the rear wall of the block of coal as cutting progresses to form an opening in the
30 mine wall of such size as to provide clearance for said second base as the apparatus is advanced along the coal face, receiving means on said second base for receiving the broken down coal and
35 cooperating conveying means for conveying the coal from said receiving means laterally away from the coal face, and propelling means for the apparatus for moving said bases in unison bodily along the coal face.

12. In a mining and loading apparatus, a portable base movable along a coal face outside there-
40 of in a direction parallel with the coal face, horizontal kerf cutting means mounted on said base for cutting simultaneously parallel horizontal kerfs in the mine wall, a portable base movable along the coal face inside the latter in a direction parallel with the coal face, vertical kerf cutting means mounted on said second base for cutting a vertical kerf rearwardly of said horizontal kerfs, said kerf cutting means cooperating to cut out a block of coal from the mine wall, breaking down
45 means mounted on said second base and arranged inside the coal face rearwardly of the forward extremity of said vertical kerf forming means for breaking down the rear wall of the block of coal as cutting progresses to form an opening in the
50 mine wall of such size as to provide clearance for said second base as the apparatus is advanced along the coal face, a shovel on said second base for receiving the broken down coal and
55 cooperating conveying means, and propelling means for the apparatus for moving said bases in unison bodily along the coal face.

13. In a mining and loading apparatus, a portable base movable along a coal face outside there-
60 of in a direction parallel with the coal face, horizontal kerf cutting means mounted on said base for forming parallel superimposed horizontal kerfs in the mine wall to form a block of coal attached at its forward and inner sides to the
65
70
75

coal seam, a portable base movable along the coal face inside the latter in a direction parallel with the coal face, a vertical kerf forming means mounted on said second base for cutting a vertical rear wall kerf intersecting said horizontal kerfs to form a core of coal, dislodging means mounted on said second base inside the coal face and acting on the rear wall of the core of coal rearwardly of the forward extremity of said vertical kerf forming means for breaking down the core to form an opening in the mine wall of such size as to provide clearance for said second base as the apparatus is advanced along the coal face, conveying means on said second base for receiving the broken down coal and conveying the broken coal rearwardly of said dislodging means, and propelling means for the apparatus for moving said bases in unison bodily along the coal face.

14. In a mining and loading apparatus, a portable base movable along a coal face outside thereof in a direction parallel with the coal face, horizontal kerf cutting means mounted on said base for forming parallel superimposed horizontal kerfs in the mine wall to form a block of coal attached at its forward and inner sides to the coal seam, a portable base movable along the coal face inside the latter in a direction parallel with the coal face, a rearwardly located vertical kerf forming means mounted on said second base for cutting a vertical rear wall kerf intersecting said horizontal kerfs to form a core of coal rearwardly of said horizontal kerf forming means, dislodging means mounted on said second base inside the coal face and acting on the rear wall of the core of coal rearwardly of the forward extremity of said vertical kerf forming means for breaking down the core to form an opening in the mine wall of such size as to provide clearance for said second base as the apparatus is advanced along the coal face, conveying means on said second base for receiving the broken down coal and conveying the broken coal rearwardly of said dislodging means, and propelling means for the apparatus for moving said bases in unison bodily along the coal face.

15. In a mining and loading apparatus, a portable base movable along a coal face outside thereof in a direction parallel with the coal face, horizontal kerf cutting means mounted on said base for forming parallel superimposed horizontal kerfs in the mine wall to form a block of coal attached at its forward and inner sides to the coal seam, a portable base movable along the coal face inside the latter in a direction parallel with the coal face, a rearwardly located vertical kerf forming means mounted on said second base for cutting a vertical rear wall kerf intersecting said horizontal kerfs to form a core of coal rearwardly of said horizontal kerf forming means, dislodging means mounted on said second base inside the coal face and acting on the rear wall of the core of coal rearwardly of the forward extremity of said vertical kerf forming means for breaking down the core to form an opening in the mine wall of such size as to provide clearance for said second base as the apparatus is advanced along the coal face, conveying means on said second base for receiving the broken down coal and conveying the broken coal rearwardly of said dislodging means, conveying means onto which said first mentioned conveying means discharges for conveying the broken coal laterally from the second base, and propelling means

for the apparatus for moving said bases in unison bodily along the coal face.

16. In a mining and loading apparatus, a portable base movable along a coal face outside thereof in a direction parallel with the coal face, horizontal kerf cutting means mounted on said base and projecting laterally therefrom at right angles to said base for cutting simultaneously parallel horizontal kerfs in the mine wall, a portable base movable along the coal face inside the latter in a direction parallel with the coal face, vertical kerf cutting means mounted on said second base for cutting a rear wall vertical kerf rearwardly of said horizontal kerfs, said kerf cutting means cooperating to cut a block of coal from the mine wall, breaking down means mounted on said second base and arranged rearwardly of the forward extremity of said kerf cutting means for breaking down the rear wall of the block of coal to form an opening in the mine wall of such size as to provide clearance for said second base as the apparatus is advanced along the coal face, receiving means on said second base for receiving the dislodged coal and cooperating conveying means for conveying the dislodged coal laterally from the coal face, and propelling means for the apparatus for moving said bases in unison bodily along the coal face.

17. In a mining and loading apparatus, a portable base movable along a coal face outside thereof in a direction parallel with the coal face, means mounted on said base for simultaneously cutting parallel horizontal kerfs in the mine wall, respectively at the floor and roof levels, a portable base movable along the coal face inside the latter in a direction parallel with the coal face, means mounted on said second base and arranged rearwardly of said horizontal kerf cutting means for cutting a rear wall vertical kerf, said kerfs extending in a direction parallel with the coal face and cooperating to form a core of coal, means on said second base inside the coal face for dislodging sections of the core as cutting progresses thereby to form an opening in the mine wall of such size as to provide clearance for said second base as the apparatus is advanced along the coal face, receiving means on said second base for receiving the dislodged coal and cooperating conveying means for conveying the dislodged coal laterally from the coal face, propelling means for the apparatus for moving said bases in unison bodily along the coal face, and a motor carried by said first base for actuating said horizontal kerf cutting means and said propelling means.

18. In a mining and loading apparatus, a portable base movable along a coal face outside thereof in a direction parallel with the coal face, means mounted on said base for simultaneously cutting parallel horizontal kerfs in the mine wall, respectively at the floor and roof levels, a portable base movable along the coal face inside the latter in a direction parallel with the coal face, means mounted on said second base and arranged rearwardly of said horizontal kerf cutting means for cutting a rear wall vertical kerf, said kerfs extending in a direction parallel with the coal face and cooperating to form a core of coal, means on said second base inside the coal face for dislodging sections of the core as cutting progresses thereby to form an opening in the mine wall of such size as to provide clearance for said second base, as the apparatus is advanced along the coal face, propelling means for said bases for moving said bases in unison bodily along the coal

face, a motor carried by said first base for actuating said horizontal kerf cutting means and said propelling means, and a motor carried by said second base for actuating said vertical kerf cutting means and said dislodging means.

19. In a mining and loading apparatus, horizontal kerf cutting means including horizontal kerf cutters pivotally mounted for horizontal swinging movement about aligned vertical axes for cutting simultaneously parallel horizontal kerfs in the mine wall, vertical kerf cutting means arranged at the rear of said horizontal kerf cutters so as to clear the latter during horizontal swinging movement thereof for cutting a rear wall vertical kerf rearwardly of said horizontal kerf, and breaking down means arranged rearwardly of the forward extremity of said vertical kerf cutting means for breaking down the rear wall of a block of coal formed by said horizontal and vertical kerf forming means, and means for actuating said kerf forming means and for horizontally swing said kerf cutters about their pivots.

20. In a mining and loading apparatus, a portable base movable along a coal face outside thereof in a direction parallel with the coal face, means mounted on said base for simultaneously cutting parallel horizontal kerfs in the mine wall, respectively at the floor and roof levels, a portable base movable along the coal face inside the latter in a direction parallel with the coal face, means mounted on said second base and arranged rearwardly of said horizontal kerf cutting means for cutting a rear wall vertical kerf, said kerfs extending in a direction parallel with the coal face and cooperating to form a core of coal, means on said second base inside the coal face for dislodging sections of the core as cutting progresses thereby to form an opening in the mine wall of such size as to provide clearance for said second base as the apparatus is advanced along the coal face, receiving means on said second base for receiving the dislodged coal and for conveying the dislodged coal laterally from the coal face, means extending between said bases outside the coal face for connecting said second base to said first base for movement therewith, and propelling means for the apparatus for moving said bases in unison bodily along the coal face.

21. In a mining and loading apparatus, a portable base movable along a coal face outside thereof in a direction parallel with the coal face, means mounted on said base for simultaneously cutting parallel horizontal kerfs in the mine wall respec-

tively at the floor and roof levels, a portable base movable along the coal face inside the latter in a direction parallel with the coal face, means mounted on said second base for cutting a rear wall vertical kerf, said horizontal and vertical kerfs extending in a direction parallel with the coal face and cooperating to form a core of coal, means carried by said second base for receiving broken down sections of said core of coal and for conveying the broken coal laterally away from the coal face, and propelling means for the apparatus for moving said bases in unison bodily along the coal face.

22. In a mining and loading apparatus, a portable base movable along a coal face outside thereof in a direction parallel with the coal face, horizontal kerf cutting means mounted on said base for cutting simultaneously parallel horizontal kerfs in the mine wall, a portable base movable along the coal face inside the latter in a direction parallel with the coal face, vertical kerf cutting means mounted on said second base for cutting a vertical kerf intersecting said horizontal kerfs, said horizontal and vertical kerf cutting means cooperating to cut out a block of coal from the mine wall, receiving means on said second base for receiving broken down sections of the core and cooperating conveying means for conveying the broken coal from said receiving means laterally away from the coal face, and propelling means for the apparatus for moving said bases in unison bodily along the coal face.

23. In a mining and loading apparatus, a portable base movable along a coal face outside thereof in a direction parallel with the coal face, horizontal kerf cutting means mounted on said base for forming parallel superimposed horizontal kerfs in the mine wall to form a block of coal attached at its forward and inner sides to the coal seam, a portable base movable along the coal face inside the latter in a direction parallel with the coal face, vertical kerf forming means mounted on said second base for cutting a vertical rear wall kerf intersecting said horizontal kerfs to form a core of coal, conveying means on said second base for receiving broken down sections of the core and conveying the broken coal rearwardly of said kerf forming means and laterally away from the coal face, and propelling means for the apparatus for moving said bases in unison bodily along the coal face.

CHARLES B. OFFICER.

CERTIFICATE OF CORRECTION.

Patent No. 2,077,432.

April 20, 1937.

CHARLES B. OFFICER.

It is hereby certified that error appears in the printed specification of the above numbered patent requiring correction as follows: Page 6, second column, line 60, claim 18, for the word "well" read wall; page 7, first column, line 22, claim 19, for "swing" read swinging; and that the said Letters Patent should be read with these corrections therein that the same may conform to the record of the case in the Patent Office.

Signed and sealed this 21st day of December, A. D. 1937.

Henry Van Arsdale,

Acting Commissioner of Patents.
